UNITED STATES PATENT OFFICE.

VIRGINIUS Z. CARACRISTI, OF BRONXVILLE, NEW YORK, ASSIGNOR TO LOCOMOTIVE
PULVERIZED FUEL COMPANY, A CORPORATION OF DELAWARE.

APPARATUS FOR HANDLING PULVERIZED FUEL.

Application filed August 30, 1920. Serial No. 407,042.

To all whom it may concern:

Be it known that I, VIRGINIUS Z. CARACRISTI, a citizen of the United States, residing at Bronxville, in the county of Westchester and State of New York, have invented certain new and useful Improvements in Apparatus for Handling Pulverized Fuel, of which the following is a specification.

10 This invention relates to a device for handling pulverized fuel and particularly to an improved construction of screw conveyor mechanism for feeding the fuel from a supply bin to the pipe or pipes which lead 15 to the furnace.

It has for its object the provision of what I have termed a split feeder wherein the screw conveyor is housed in a two-part casting, the parts of which are easily secured 20 together after the conveyor has been put in place. In general my improvement contemplates the provision of a feeder composed of a number of separable castings or members which are easy to manufacture as 25 independent units and readily and simply assembled at the point of installation.

It is also an object of my invention to provide a split feeder having the characteristics above enumerated which embodies suitable 30 means for supplying air to the fuel and thoroughly mixing it therewith prior to its discharge or delivery into the conduit which conveys it to the furnace. This air supply means comprises a chamber adjacent to the fuel inlet hopper through which the conveyor extends. It also involves the provision 35 of a separable guard member surrounding the conveyor where it passes through the air supply chamber, said guard member being held in place between two of the castings forming the feeder.

These and further objects and advantages will more clearly appear in connection with the following description of the accompanying 45 drawings which illustrate my invention in its preferred form and wherein

Figure 1 is a vertical longitudinal section through my improved split feeder; Figure 2 is a side elevation of the device; 50 Figure 3 is a plan view of the base casting showing the conveyor guard member in longitudinal section; Figure 4 is a section on the line 4-4 of Figure 1; Figure 5 is a section on the line 5-5 of Figure 1; and

Figure 6 is a partial end elevation of Fig- 55 ure 2 illustrating details of the construction.

Referring to the drawings it will be seen that my improved feeder comprises an upper casting A having a fuel inlet opening or hopper 1 and a lower or base casting B. 60 Horizontally disposed flanges 2 and 3 on these castings provide a convenient means for clamping them together by means of the nuts and bolts 4. The housing formed by these two castings is open ended and the screw conveyor 5 with its axle 6 extends through the open ends. One open end is closed by the member C secured to the housing by means of the bolts 7 and carrying suitable bearing means for the axle or shaft 70 6. A sprocket or pinion or other suitable driving wheel 8 is secured to the shaft 6 immediately outside the closure member C. The other open end is closed by the discharge casting or casing D which is secured 75 to the housing by means of the bolts 9. The closure members and the housing are provided with suitable vertically disposed flanges 10 and 11 as shown. The discharge casting D carries the bearing means for the 80 other end of the conveyor shaft 6, such bearing means being located within a housing 12.

The openings 13 around the upper margin of the inlet or hopper 1 provide desirable means for securing the feeder to the 85 bottom of a fuel supply bin, not shown.

Between the outlet casting D and the hopper 1 the castings forming the housing are constructed to provide an air supply chamber E having an air inlet means at 14. 90 The screw conveyor extends through this air chamber and a guard or conduit 15 is placed around it so that the fuel can be conveyed to the point at which it enters the outlet casting D where it is mixed with the air entering at 14. A bladed agitating member 16 is mounted for rotation upon the shaft 6 at this point and aids in thoroughly mixing the fuel and air.

The inner end of the conduit or guard 100 member 15 is flanged as at 17 for suitable connection and support from a recess in the housing, as clearly shown in Figure 1. The outer end of the conduit 15 is supported in its proper position by means of the four inwardly projecting feet 18 formed on the inner wall of the chamber E.

The upper casting is provided at one end

with a door 19 and at the other end with a slide 20 by means of which the supply of fuel from the bin may be regulated in quantity or cut off entirely.

5 At a point immediately above the agitator 16, the outlet or discharge casing D is provided with an opening and a suitable cap or cover 21 therefor which is held in place by means of the strap or yoke 22 pivoted at 10 each side upon the pins 23 and provided with a thumb adjusting screw 24 designed to cooperate with the flat surface 25.

It will be apparent that the various castings or members composing my improved 15 feeder as above outlined can be easily manufactured as independent units and that their assembly can be very conveniently, quickly and easily accomplished. The structure 20 after assembly is strong and rigid and access to the interior is provided for through the openings closed by the door 19 and the cap or cover 21.

In assembly the guard is first placed 25 around the conveyor 5 after which these two parts are clamped between the upper and lower castings A and B. The closure member C and the outlet casing D carrying their respective bearings are then applied and secured to the housing by means of the bolts 7 30 and 9 after which the driving gear 8 may be affixed to the shaft 6. It will be understood, of course, that the shaft 6 is introduced into the conveyor proper 5 and the latter secured thereto in any suitable or desired manner. 35 The shaft 6 may be introduced from either end, in one case the gear 8 being the last member to be applied and in the other case the agitator 16. It will be apparent to those skilled in the art that a number of methods 40 of assembly might be utilized all of which would, however, be approximately equally simple, expeditious and convenient.

I claim:

45 1. A device for handling pulverized fuel comprising, in combination, an upper casting having a fuel inlet, a base casting, means on the said castings whereby they may be fastened together to form a housing, a fuel outlet opening in the housing, a screw conveyor projecting through the outlet opening,

an air admission chamber supplying air to the fuel at the outlet, and a separable member surrounding the conveyor where it extends through the air chamber, said member being held in place between the two castings. 55

2. A device for handling pulverized fuel comprising, in combination, an upper casting, a base casting, means for securing said castings together to form a housing comprising a fuel inlet hopper, an air supply chamber adjacent the hopper, a screw conveyor extending across the bottom of the hopper and through the air chamber, a fuel outlet from the air chamber, and a separable member surrounding the conveyor from the hopper to the fuel outlet, said separable member being held in place between the two castings. 60 65

3. A device for handling pulverized fuel comprising, in combination, a split housing 70 having a fuel inlet opening, a neck at one end and a tubular member clamped in place at the other end, a conveyor in said housing surrounded at one end by the neck and at the other end by the tubular member, the 75 ends of the conveyor projecting outwardly beyond the housing, a bearing detachably connected to the neck portion of the housing and a discharge outlet casting detachably connected to the other end of the housing 80 having a bearing detachably connected thereto.

4. A feeder for pulverized material comprising a substantially horizontally disposed screw conveyor, a two part housing split 85 substantially horizontally and a tubular member surrounding an end portion of the screw, said two part housing and said tubular member cooperating when assembled to divide the housing into an inlet compartment and a separate compartment surrounding said member, and means for admitting air to the last mentioned compartment together with an elbow like discharge casing secured to the air compartment and a shaft 90 for the screw having a bearing in the discharge casing. 95

In testimony whereof I have hereunto signed my name.

VIRGINIUS Z. CARACRISTI.
